UNITED STATES PATENT OFFICE

BERT R. HEIMENDINGER, OF BRITT, IOWA

VALVE PUSH ROD

Application filed May 20, 1929. Serial No. 364,556.

This invention relates to an improvement in valve push rods for internal combustion engines, and particularly applies to the type of engine known as overhead valve kind, and 5 an object of the invention is to overcome the difficulty heretofore experienced in this type of engine, of securing noiseless and efficient valve operating mechanism.

Another object of the invention is to provide for clearance in the push rod itself, whereas it has been heretofore the practice to provide clearance where the push rod and valve stem contact with the opposite ends of the rocker arm, while at the same time to provide 15 a fluid film at the points of clearance in the push rods to prevent noise and undue wear and tear on the abutting parts.

Further objects of the invention are to provide in a manner as hereinafter set forth, a 20 push rod of the character referred to, which is strong, compact and durable, thoroughly reliable in its operation, highly efficient for its intended purpose, very simple in its method of assembly, adaptable for use in standard overhead 25 valve types of internal combustion engines and comparatively inexpensive to manufacture and install.

With the foregoing and other objects in view, the invention consists in the novel construction, combination, and arrangement of parts as will be hereinafter more specifically described and illustrated in the accompanying drawings, wherein is disclosed an embodiment of the invention, but it is to be understood that changes, variations and modifications 35 may be resorted to, without departing from the spirit of the claims hereunto appended.

In the drawings, wherein like reference 40 characters denote corresponding parts throughout the several views:

Figure 1 is a fragmentary elevation, partly in section, of a sectional push rod in accordance with this invention.

Figure 2 is the same view of a modified form thereof.

Figure 3 is the same view of a further modification thereof, and

Figure 4 is the same view of a still further 50 modification thereof.

It has been customary in the construction of the overhead type of valve in an internal combustion engine, to provide clearance of approximately .008 inches between one end of the rocker arm and the upper end of the 55 valve stem. At this point it has been considered impractical to provide lubrication between the valve stem and the end of the rocker arm and from this source comes most of the noise and rattle which this invention 60 aims to overcome. The other end of the rocker arm which is in communication with the upper end of the push rod is usually provided with a ball joint which is seated in a socket at the upper ends of the push rod. 65 Very little clearance is required at this point, and fine adjustment is usually provided. It is to be noted that the socket may be provided with lubrication which has the tendency to 70 eliminate the slapping or noise at this end of the rocker arm. It is to be understood that the present invention is particularly adapted to that type of rocker arm construction which has a ball joint on the push rod end of the 75 rocker arm, which is seated in a socket formed on the upper end of the push rod.

Bearing the foregoing in mind, and referring particularly to the drawings, 5 indicates generally a sectional push rod in accordance with this invention and the upper 80 section thereof is indicated at 6, while the lower section thereof is indicated at 7. On the lower end of the upper section 6 is formed a socket 8, the outer walls of which are of a greater diameter than the remaining portions 85 of the upper section and is provided with an axially extending opening 9, which forms a snug but movable fit between the upper ends of the lower section 7 which rides in the 90 socket.

The snug fit prevents undue escape of the oil, which will be presently made clear.

A laterally projecting annular shoulder 10 is formed intermediate the opposite ends of the lower section in spaced relation to the 95 lower edges of the socket 8 and a helical coil spring 11 is circumposed about the lower section 7 having the opposite ends thereof abutting against the lower edges of the socket 8 and the upper edge of the shoulder 10. The 100

lower end 12 of the lower section 7 may be modified in any suitable manner to engage the cam (not shown in the drawings) of an internal combustion engine which operates the push rod in the conventional manner. Extending along the axis of the upper section 6 from the socket (not shown in the drawings) is a circular passage 13, that terminates in communication with the center of the inner wall 14 of the socket 8. The passage 13 conducts oil from the socket connection with the rocker arm down into the socket 8 and forms a film between the upper end 15 of the lower section 7 and the inner wall 14 of the socket to cushion the effect of the noise and at the same time lubricate the abutting parts. By reason of this structure, it has been found by experiment a clearance of as much as .015 inches may be provided between the inner wall of the socket and the upper end of the lower section without increasing the noise or causing any ill effect on the operation of the valve. What has been said with respect to the form shown in Figure 1, in regard to the clearance, applies to the other modified forms of the invention to be presently referred to.

In the modified form of the invention shown in Figure 2 of the drawings and referring particularly thereto, the only difference in structure involved therein is that a circular disc 16 having a plurality of radiating channels 17, 18, on the upper and lower faces thereof is interposed in the socket 8 between the inner wall 14 thereof and the upper end 15 of the lower section 7. An opening 19 extends through the axis of the disc 16 and communicates with the passage 13 for conveying the oil film therethrough. The channels 17, 18 provide minute reservoirs and also cushions between the abutting parts 15 of the lower section and the inner wall 14 of the socket.

In the modification shown in Figure 3 of the drawings and referring particularly thereto, all parts are formed in a similar manner with the exceptions to be noted. The exceptions being that the inner wall of the socket is formed with an arcuate concavity 20 and the upper end 15 of the lower section 7 is also formed with an arcuate concavity 21, for seating between the parts a ball 22.

In the modification shown in Figure 4, and referring particularly thereto, all of the parts are formed similar to Figure 1, with the exceptions to be noted. The inner wall of the socket is formed with a conical-shaped concavity 23, and the upper end 15 of the lower section 7 is likewise formed with an inverted conical concavity 24, which is aligned with the concavity 23.

Movably supported between the aligned concavities is a separator member 25 of integral double conical formation.

It is to be noted that the disc 16, the

ball 22, and the member 25, are separator members.

In the application of the push rod in accordance with this invention, all of the clearances heretofore used between the upper end of the push rod and the one end of the rocker arm and between the valve stem and the other end of the rocker arm may be eliminated by reason of the fact that clearance is provided by the present invention. Another difficulty overcome by the present invention is that in providing clearance between the valve stem and the rocker arm of the other construction when great clearance occurs by reason of wear and tear or for other reasons, there is danger of burning or scoring the valve to a point of making the same stick in its seat.

The spring 11 when in use will hold all contacting parts snugly together, that, the top of the valve stem with one end of the rocker arm, the opposite end of the rocker arm with the upper end of the push rod to prevent noise at their points, while the clearance is maintained at the upper and lower portions of the sectional push rod and at 16, 22 and 25. Since the points of contact between the inner wall of the socket and upper end of the push rod or the disk, the ball and the double cone are cushioned with a film of oil the noise is eliminated and it is to be noted that the invention as disclosed in Figures 2, 3 and 4 provides two oil films to overcome this noise. The disk 16 may be replaced by a number of abutting disks which will have an increased number of films for the same purpose.

What is claimed is:

1. In combination with an internal combustion engine, a sectional push rod, the upper of said sections being formed with a socket and the upper end of the lower section movably confined in said socket, a shoulder formed on said other section intermediate the ends thereof and in spaced relation to the edges of said socket, a coil spring circumposed about said other section having its opposite ends in abutment with said shoulder and the edges of the socket for urging said sections apart, said upper section having a passage extending axially therethrough from the upper end and in communication with said socket for conducting oil into the socket to form a film to provide a cushion for the abutting parts.

2. In combination with an internal combustion engine, a sectional push rod, the upper of said sections being formed with a socket and the upper end of the lower section movably confined in said socket, a shoulder formed on said other section intermediate the ends thereof and in spaced relation to the edges of said socket, a coil spring circumposed about said other section having its opposite ends in abutment with said shoulder and the edges of the socket for urging said sections apart, said upper section having a passage ex-

tending axially therethrough from the upper end and in communication with said socket for conducting oil into the socket to form a film to provide a cushion for the abutting parts, the point of discharge of said passage into said socket being in the center of the abutting parts.

3. In combination with an internal combustion engine, a sectional push rod, the upper of said sections being formed with a socket and the upper end of the lower section movably confined in said socket, a shoulder formed on said other section intermediate the ends thereof and in spaced relation to the edges of said socket, a coil spring circumposed about said other section having its opposite ends in abutment with said shoulder and the edges of the socket for urging said sections apart, said upper section having a passage extending axially therethrough from the upper end and in communication with said socket for conducting oil into the socket to form a film to provide a cushion for the abutting parts, the point of discharge of said passage into said socket being in the center of the abutting parts, a separator member movably confined in the socket between the inner wall thereof and the upper end of the lower section.

30 4. In combination with an internal combustion engine, a sectional push rod, the upper of said sections being formed with a socket and the upper end of the lower section movably confined in said socket, a shoulder formed on said other section intermediate the ends thereof and in spaced relation to the edges of said socket, a coil spring circumposed about said other section having its opposite ends in abutment with said shoulder and the edges of the socket for urging said sections apart, said upper section having a passage extending axially therethrough from the upper end and in communication with said socket for conducting oil into the socket to form a film to provide a cushion for the abutting parts, the point of discharge of said passage into said socket being in the center of the abutting parts, a separator member movably confined in the socket between the inner wall thereof and the upper end of the lower section, said upper end of the lower section provided with a concavity and the inner wall of said socket provided with a concavity in alignment with said first mentioned concavity to provide a seat for said separator member.

In testimony whereof I affix my signature.
BERT R. HEIMENDINGER.
